UNITED STATES PATENT OFFICE.

EDWIN ARCHER TURNER, OF PITTSBURGH, PENNSYLVANIA, ASSIGNOR TO LOCOMOTIVE STOKER COMPANY, A CORPORATION OF PENNSYLVANIA.

LOCOMOTIVE STOKER.

Application filed July 8, 1926. Serial No. 121,110.

This invention relates to stokers of the scatter feed type and more particularly to stokers of this character in which the fuel is delivered in two separate streams upon a distributor plate extending into the fire box thru the firing door opening, from which plate it is scattered over the grate by means of steam jets.

The object of the invention is to provide improved means for raising the fuel to the points of discharge upon the chutes which deliver to the two side portions of the distributor plate; to secure compactness and to improve the location of the fuel elevator so as to avoid substantially all encroachment upon the areas of the backhead of the boiler which, as locomotives are now organized, are required for the emplacement of other essential devices such as gauges and the like. A further object is to provide for the regulation of the two streams of fuel to facilitate the trimming of the fire.

While in its details the invention may be variously embodied, a desirable, and so far as now advised, preferred form of construction is hereinafter described and is illustrated in the accompanying drawings in which

Fig. 1 is a detail elevation of the rear end of a locomotive with the improved stoker applied thereto, a portion of the latter being shown in section and some portions of its internal construction being indicated by dotted lines.

Fig. 2 is a detail central, longitudinal, vertical section of the rear end of the locomotive with the stoker applied thereto.

Fig. 3 is a sectional detail on line 3—3 of Fig. 2, some of the parts being omitted, and

Fig. 4 is a detail, partly in section, of the driving mechanism of the stoker.

A conventional form of backhead of the locomotive boiler is represented at 10 and is shown as being provided with the usual hand firing door opening 11; a portion of the grate is shown at 12; and of the locomotive frame at 13. The deck of the cab is shown at 14 and a transfer conveyor for bringing the fuel forward from the engine tender is shown at 15.

The conveyor 15 delivers into the lower

end of an elevating conduit 16, to which it may be connected by a ball joint 17.

The conduit 16 is located on the longitudinal, median line of the locomotive, and extends upwardly thru the deck 14 and substantially parallel with the backhead 10, from which it is spaced a short distance. A pair of outwardly bowed conduits 18, 19 each of substantially one-half the capacity of the conduit 16 extend upwardly from the latter, and flank the fire door opening 11. The open in-turned ends of the conduits 18, 19 are slightly within the side margins of the fire door opening and below its upper margin.

The box or casing 20, securely bolted to the backhead 10, encloses the opening 11 and is provided in its outer wall with a corresponding opening 21, which may be closed by suitable doors, not shown. The conduits 18, 19 may be cast integrally with the casing 20, as shown, their converging lower ends extending to the top of the conduit 16 and being securely bolted thereto.

Mounted within the casing 20 are a pair of chutes 22, one below the open end of each of the conduits 18, 19 and both being inclined downwardly toward a distributor plate 24 which extends thru the opening 11 and into the fire box of the boiler. These chutes are provided with stems 25, 26 which are pivoted as shown at 27 within the casing 20 so that they may swing laterally for the purpose of discharging fuel either adjacent to the side margin of the plate 24 or to its middle portion. Power may be applied in any suitable manner for causing the oscillation of the chutes, as thru a control box 28, attached to the backhead 10 and containing mechanism whereby the application of such power may be controlled and regulated. This mechanism is not shown in detail for the reason that it is well known and does not constitute a part of the present invention.

A dividing vane or plate 29 is pivotally mounted at the juncture of the conduits 18, 19, being carried by a spindle 30 journaled in the side walls of these conduits, from which it depends, and in effect forms a downward continuation of the upper wall of each of the conduits and splits the column of coal as

cending thru the conduit 16 into two streams. This vane may be adjusted by means of a crank arm 31 on the outer end of the spindle 30, and which carries at its outer end a stud 32 cooperating with suitable apertures in a fixed quadrant plate 33. When swung laterally in either direction, the vane 29 cramps the receiving end of one of the conduits 18, 19 and enlarges that of the other, thereby 10 correspondingly varying the amount of fuel entering each.

The distributor plate 24 is secured in place in any desired manner. In order that it may be easily inserted and removed, it 15 may be provided with a backwardly extending hooked arm 34 cooperating with a socketed lug 35 formed on the inner face of the bottom wall of the casing 20. The forward end of the plate 24 rests by gravity upon the 20 lower margin of the opening 11, thru the medium of down standing flanges 36. An opening 37 in the bottom wall of the casing 20 permits the entrance of air under the plate 24 to protect the latter from the intense heat of the furnace. 25

Within the conduit 16, there is housed an elevating screw 38, the lower end of its shaft 39 extending thru the bottom of the conduit and carrying a worm gear 40. 30 Power for driving the screw 38 and the transfer screw 41 is derived from a motor 42 which may be suitably mounted on the frame of the locomotive and below the deck thereof, its shaft 43 extending transversely of the 35 vehicle and being provided with worms 44, 45 for engaging respectively the worm gear 40 and a worm gear 46, the shaft 47 of which is connected, in any suitable manner, with the shaft of the screw 41. The worm 40 45 is preferably sleeved upon the engine shaft 43 and may be locked thereto by means of a clutch element 48 splined upon the engine shaft and controlled by a shifter element 49 thru the medium of a crank arm 50 45 on the upper end of a rod 51 extending upwardly thru the deck 14.

The conduit 16 is provided with a removable panel 52 to give access to the interior of the conduit for the purpose of removing 50 any extraneous matter which may enter with the coal and clog the machinery. This panel is preferably outwardly offset as plainly shown in Fig. 2 in order that the margin of the opening which it covers may serve 55 as a shoulder to check the tendency of the ascending fuel to rotate with the elevating screw. The conduits 18, 19 are preferably given an oval form as shown in Fig. 3 to check the tendency of the fuel to rotate 60 within them.

Fuel brought forward by the transferring screw 41 is delivered directly to the elevating screw 38 and thence into the two conduits 18, 19 thru which it is forced by the 65 pressure of the last named screw and from

which it is discharged upon the chutes 22, 23, and falling upon the plate 24 is projected therefrom and scattered over the area of a grate 12 by means of steam jets issuing from a chest 53 which may be formed integrally with the plate. Chest 53 is preferably divided into two compartments to each of which leads from any suitable sources of supply steam pipes 54, 55. 70

Should the bed of fuel on the grate become uneven by reason of an excess of fuel being delivered to one side of the fire box, the vane 29 may be shifted to diminish the supply to that side and increase it to the other side of the fire box. Should a clogging occur, it will ordinarily be caused by the presence of extraneous matter, usually an iron fragment, wedging between the periphery of the elevating screw and the wall of the conduit. For the purpose of removing such object, the elevating screw is turned backwardly a short distance, and preferably before this action, the transfer screw 41 is stopped by disconnecting the clutch element 48 from the worm 45. 75 80 85 90

The upper end of the vane 29 fits within a pocket formed in the conduit wall, and at the juncture of the conduits 18, 19, the upper or pivotal end of the vane is thickened and rounded, as shown at 60, 60, the sides of the 95 pocket being correspondingly rounded, as shown at 61, 61. The extreme upper surface 62 of the vane is flattened and spaced from the corresponding surface 63 on the conduit wall. This structure permits the vane to be 100 easily adjusted, preventing binding due to a pocketing of coal between the vanes and the walls of the conduit and reduces the change in the wall structure of the conduits when the vane is adjusted to make an unequal division of the coal. Where there is ample 105 room, the flattening at 62 may be omitted and the complementary surface of the vane and the wall may be made cylindrical throughout. By flattening the surfaces as shown, 110 greater clearance is afforded between the vane and the fire door opening. 115

The box or casing 20 and the branch conduits form a unit that may be made substantially uniform for a large number of locomotives while the straight section of the elevator or the conduit 16 together with its elevating screw will vary in length with different locomotives. 120

The cool air passing thru the opening 37 along the under side of the distributing plate 24 and against the flanges 36 performs an important cooling function and greatly increases the period of service that the plate will endure. 125

I claim as my invention:

1. In a stoker for a locomotive having a backhead and a firing opening therein, in combination, a straight elevating conduit below the firing opening, a pair of conduits 130

branching outwardly from the upper end of the elevating conduit and curved inwardly at their upper ends, means within the first-named conduit for forcing fuel therethrough and through the pair of conduits, and chutes receiving from the branching conduits and delivering into the firing opening.

2. In a stoker for a locomotive having a backhead and a firing opening therein, in combination, an elevating conduit below the firing opening, a pair of conduits branching outwardly from the upper end of the elevating conduit and curved inwardly at their upper ends, a screw within the elevating conduit for forcing fuel therethrough and through the pair of conduits, and swinging chutes receiving from the branching conduits and delivering into the firing opening.

3. In a stoker for a locomotive having a backhead and a firing opening therein, in combination, an elevating conduit under the firing opening, elevating means within the conduit, a pair of upwardly inclined conduits branching outwardly from the upper end of the elevating conduit and curved inwardly at their upper ends, chutes receiving from the branching conduits and delivering into the firing opening, and a dividing vane interposed between the lower ends of the branching conduits.

4. In a stoker for a locomotive having a backhead and a firing opening therein, in combination, an elevating conduit under the firing opening, elevating means within the conduit, a pair of upwardly inclined conduits branching outwardly from the upper end of the elevating conduit and curved inwardly at their upper ends, chutes receiving from the branching conduits and delivering into the firing opening, and an adjustable dividing vane interposed between the lower ends of the branching conduits.

5. In a stoker for a locomotive having a backhead with a firing opening therein, the combination of an elevating conduit extending upwardly along the backhead below the firing opening, a pair of conduits receiving fuel from the first conduit, said pair of conduits diverging outwardly below the firing opening and then curving upwardly and inwardly to points adjacent to the top of the firing opening, elevating means within the first conduit to force fuel thru the branch conduits and distributing means receiving fuel from the branch conduits.

6. In a stoker for a locomotive having a backhead with a firing opening therein, the combination of an elevator casing including a single conduit extending upwardly along the backhead and forked to form two branch conduits diverging below the firing opening, then curving upwardly and inwardly and terminating adjacent to the upper part of the firing opening, an elevator screw in the single conduit for forcing fuel thru the

branch conduits, and distributing means receiving fuel from the branch conduits, said casing being divided below and adjacent to the fork and said screw terminating adjacent to the division.

7. In a stoker for a locomotive having a backhead with a firing opening therein, the combination of an elevator casing including a single conduit extending upwardly along the backhead and forked to form two branch conduits diverging below the firing opening, then curving upwardly and inwardly and terminating adjacent to the upper part of the firing opening, a box secured to the backhead about the firing opening and inclosing the upper end portions of the branch conduits, an elevator screw in the single conduit for forcing fuel thru the branch conduits, and distributing means receiving fuel from the branch conduit, said casing being divided below and adjacent to the fork and said screw terminating adjacent to the division.

8. In a stoker for a locomotive having a backhead and a firing opening therein, the combination with an elevating conduit located below the firing opening, a casing inclosing such opening and attached to the elevating conduit, such casing comprising a pair of branch conduits receiving from the elevating conduit and bowing outwardly, their upper ends delivering into the chamber of the casing, and a screw within the elevating conduit for forcing fuel therethrough and through the branch conduits.

9. In a stoker for a locomotive having a backhead with a firing opening therein, the combination of a single elevator conduit extending upwardly along the backhead and forked to form two branch conduits diverging below the firing opening, then curving upwardly and inwardly and terminating adjacent to the upper part of the firing opening, an elevating screw in the single conduit for forcing fuel thru the branch conduits, said branch conduits being of non-circular cross section, and distributing means receiving fuel from the branch conduits.

10. The combination of a locomotive including a backhead having a firing opening communicating with the firebox, a stoker including a casing having a support adjacent to the lower portion of the firing opening, a distributor projecting into the firebox, a hook at the rear end of the distributor adapted to engage the support and prevent forward movement of the distributor, and means on the bottom of the distributor for engaging with the backhead at the bottom of the firing door to prevent rearward movement of the distributor.

11. The combination of a locomotive including a backhead having a firing opening communicating with the firebox, a stoker including a casing having a support adja-

cent to the lower portion of the firing opening, a distributor including a plate projecting through the firing opening into the firebox, a hook on the rear portion of the plate **5** engaging said support to prevent forward movement of the distributor and downward tilting of its front end, and lugs on the

bottom of the distributor cooperating with the backhead at the bottom of the fire door to prevent rearward movement of the distributor. **10**

In testimony whereof I affix my signature.

E. ARCHER TURNER.
